INTERNAL COMBUSTION ENGINE

James W. Lacy, Dallas, Tex., assignor to
Heuschober Engineering Corporation, Fort
Worth, Tex.

Application February 1, 1941, Serial No. 376,945

4 Claims. (Cl. 123—51)

This invention relates to internal combustion engines of that general type in which one or more cylinders are provided with two pistons arranged to be forced apart by the explosion.

The general object of the invention is to provide an engine of this type which is capable of smoother operation, and with fewer moving parts which might wear out and otherwise cause trouble.

One of the particular objects of the invention is the provision of a pumping chamber and a by-pass chamber co-operating with the stroke of the piston in connection with a novel valve construction, whereby the gaseous vapor or air mixture is drawn into the pumping chamber during the total stroke of the piston. The assembling of these parts and the operation thereof also includes that during the firing stroke of the piston, the combustible mixture is compressed in the pumping chamber or discharged into the by-pass chamber from which point the mixture passes into the cylinder or cylinders during certain positions of the valve.

Another important object of the invention is the valve construction, which provides a separate section for each cylinder employed and so arranged that one rotatable element may carry the valves for the number of cylinders used according to the capacity of the engine.

The invention also includes a construction which embodies the utilization of herring-bone gears and the method herein described for mounting the gears whereby the power take-off of the engine may be had from either crank-shaft or from any one of the gears in the gear train.

With the above and other and further objects in view, the invention may be readily understood from a perusal of the following detailed description, taken in connection with the accompanying drawings and in the drawings:

Figure 1 is a vertical sectional view through an internal combustion engine constructed in accordance with the invention, the view being partly broken away;

Figure 2 is a schematic view of the gear train;

Figure 3 is a fragmentary sectional view showing one of the gears and the manner of mounting the same to the casing of the engine;

Figure 4 is a cross-sectional view of Figure 1, the view being taken along the line 4—4 thereof;

Figure 5 is a fragmentary detail sectional view of a modification of the piston ports, Figure 6 being a sectional view of Figure 5, had on the line 6—6 thereof;

Figure 7 is an enlarged detail sectional view taken on the line 7—7, Figure 1 of one of the valves and its ports, illustrating the manner of carrying a plurality of valves on one rotatable bar; and

Figure 8 is a schematic view of the valve showing its various positions.

As illustrated in the drawings, the engine consists of a casing C embodying the cylinders 1, which may be multiplied according to the size or capacity of the engine to be constructed. The cylinders are made to accommodate two pistons 2, the latter being connected to the customary crank-shafts 5 in conjunction with the pins 3 and the connecting rods 4. The two crank-shafts 5 are connected by a train of gears of the herring-bone type, the construction of the engine being especially adapted to the use of this type of gears, these gears being indicated generally at 6, Figure 2. The gears indicated at 7 are carried on the crank-shaft, and all of the gears are so arranged that each gear may be meshed with its mating gear or gears in the manner necessary with herring-bone gears, that is by movement in a line perpendicular to the center line of the gear. To this end, and as shown in Figure 3, there is provided an adapter 8 which is mounted on the gear shaft 10, along with the gear bearing 11, the shaft 10 being mounted in any suitable way in the casing C. Bolts 9 hold the gear to the adapter element 8. In this manner the mounting of the gears which connect the two crank-shafts, maintains the crankshafts in fixed relation with each other. This arrangement also provides a means for taking off the power output of the engine from either crankshaft or from any of the intermediate gears. These gears are indicated in broken lines in Figure 1, being disposed along the rear part of the engine.

The pistons 4 are relatively long in order that a stationary member 12, as shown in Figures 1 and 4, and mounted in the casing, may be held in the position shown by the supports 13. This arrangement provides for a pumping chamber 14 between the stationary member 12 and the under side of the piston, the object of which will be explained hereinafter.

Midway between the pistons 4 is placed a fuel injector or spark plug 15 depending upon the fuel and the type of engine used. The conventional forms of fuel pump injection, fuel injector, carburetor, or mixing valves and spark plugs may be used. A fuel injection pump is shown at P.

In Figures 1 and 7, also diagrammatically in Figure 8, are shown the form of special valve utilized in the engine, to control the passage of air or combustible mixture into the pumping chamber and then into the cylinder. This valve indicated at 16 is mounted on or may be made integral with a rotatable bar 17 and several of the valves, one for each cylinder, may thus be carried on this bar, each valve being placed in a section 18 of the casing C, the assembly of valves 60 being driven by the crank-shafts by meshed re-

lation of one of the gears 6 in the gear train as previously explained.

The casing section or sections 18 are provided with an intake port 19, a port 20 for the pumping chamber, and a port 21 leading to the cylinders, by way of a by-pass chamber 22.

In each of the pistons 2 are several intake ports 23, and in the cylinders are arranged exhaust ports 24 and extra intake ports 25 and also a number of intake ports 26.

In Figures 5 and 6 are shown a modification of intake means for the pistons. In this instance the plurality of piston ports 23 have been replaced by a single long port 29. A means for sealing the pumping chamber 14a from the crankcase is attained by the addition of an extension in the form of a member 30 projecting from the stationary member 12a. A plate 31 is then mounted on the member 30 and held against the inside wall of the piston 2a with several small springs 32, thus sealing the passage between the pumping chamber and the crankcase.

In addition to the air or mixture supplied by the means heretofore described, a blower B is mounted on the engine so as to discharge into an air chamber A and thence into the cylinder when the ports between the chamber and the cylinder are opened by the piston. In this manner the amount of air or mixture is increased, thus increasing the specific output of the engine. The engine also includes a suitable fly-wheel for smoothing out the firing impulses and which may be mounted on either or both crankshafts.

In the operation of the engine, and in accordance with the foregoing, it will be apparent that on the compression stroke of the pistons, the valve or valves 16 is in such position that air or combustible mixture is sucked into the pumping chamber by the ports 23 in the pistons. The valve 16 being driven either directly or indirectly by the crankshaft is so timed that the intake port 19 is closed and another opened so that the air or combustible material is compressed out of the pumping chamber 14 during the firing stroke of the piston and into the by-pass chamber 22, and from this point it passes into the cylinder when the ports are uncovered by the piston. In this manner the air or mixture has sufficient pressure to insure scavenging without crankcase compression or the aid of a blower. It will be obvious that either one or two rotary valves may be employed, depending upon the situation; however, either method may be employed so as to utilize the same principle. The cylinder ports 24, 25 and 26 may be so arranged that at one end of the cylinder are disposed intake ports while at the other end thereof are exhaust ports, and the pistons and ports so placed that the exhaust ports are opened previous to the intake ports. In order to assist in the scavenging process one or more intake ports may be placed at the exhaust end of the cylinder and opened after the exhaust ports.

Due to the herringbone type of gears employed, each gear may be installed or removed without interference with adjacent gears.

While the disclosure reveals a practical working embodiment of an internal combustion engine constructed in accordance with the invention, it will be obvious that modifications and alterations, other than those shown and suggested, may be made and which will be within the scope and meaning of the claims appended hereto.

What is claimed is:

1. In an internal combustion engine, the combination of one or more cylinders, a movable or reciprocating piston located in each end of said cylinder or cylinders, a by-pass chamber adjacent one end of each cylinder or cylinders, a fuel inlet injection and ignition means intermediate the by-pass chambers, a plurality of inlet and exhaust ports disposed in the walls of the cylinder or cylinders, a main exhaust port, a blower and an air chamber in communication with the cylinder or cylinders, a stationary member mounted in each cylinder or cylinders at each end thereof and forming a pumping chamber between the piston and said stationary member; a rotary valve at each end of said cylinder or cylinders for admitting a gaseous vapor or air mixture into said pumping chamber during the total stroke of the pistons; a crank shaft at each end of said cylinder or cylinders; each of said pistons including one or more ports for drawing the gaseous vapor or air mixture into said pumping chamber during the total stroke of the pistons; each of said pistons having a connecting rod for its adjacent crankshaft; a plurality of gears of the herringbone type providing a gear train, means for mounting said gears to connect said crankshafts to maintain said crankshafts in the same relative positions with respect to each other and for actuating said rotary valves in timed relation to opening and closing thereof.

2. An internal combustion engine as claimed in claim 1, said pistons including one or more ports, one of said ports having a means for sealing said pumping chamber from the crankcase of the engine, said means comprising an extension of said stationary member, a plate mounted on the extension and held against the wall of the piston and spring means for holding said plate in position.

3. In an internal combustion engine of one or more cylinders, a reciprocating piston in each end of each of said cylinders, a crankshaft placed at each end of said cylinders, a rod connected to each piston in the corresponding end of the cylinders, a plurality of gears of the herringbone type each gear including an adapter element and providing a gear train to connect said crankshafts to maintain the crankshafts in the same relative position and to transmit the power developed from the crankshafts to the power take-off and to the various accessories, and means for mounting and removing said herringbone gears without removing either of said crankshafts.

4. In an internal combustion engine of one or more cylinders, a reciprocating piston in each end of each of said cylinders, a crankshaft placed at each end of said cylinders, a rod connected to each piston from the corresponding crankshaft, a gear train connecting the crankshafts and providing for the power take-off, said gear train comprising one or more gear assemblies, each assembly consisting of a hub, a stationary shaft on which the hub is mounted, a rim having herringbone gear teeth and mounted on said hub in such a manner as to allow the removal or replacement of any of the gears in the gear train without necessitating the displacement of either of the crankshafts.

JAMES W. LACY.
